CLAIM

The ornamental design for a washcloth caddy and disposal unit with detachable liquid dispensing media player, as shown and described.

DESCRIPTION

FIG. 1 is a perspective view of the washcloth caddy and disposal unit with detachable liquid dispensing media player, showing our new design;

FIG. 2 is another perspective view thereof, shown in a use condition;

FIG. 3 is another perspective view thereof, shown in another use condition and in an alternate configuration;

FIG. 4 is another perspective view thereof;

FIG. 5 is a front side perspective view thereof, shown in a use condition;

FIG. 6 is an isolated front perspective view of the detachable liquid dispensing media player;

FIG. 7 is a top front perspective view thereof, shown with environment;

FIG. 8 is a left side elevation view of the washcloth caddy disposal unit without detachable liquid dispensing media player;

FIG. 9 is a front elevation view thereof;

FIG. 10 is a rear elevation view thereof;

FIG. 11 is a right side elevation view thereof;

FIG. 12 is an atop view thereof;

FIG. 13 is a bottom plan view thereof;

FIG. 14 is a rear elevation view of the detachable liquid dispensing media player;

FIG. 15 is a front elevation view thereof;

FIG. 16 is a side elevation view thereof; shown in use condition;

FIG. 17 is a top plan view thereof; and,

FIG. 18 is a bottom plan view thereof.

All elements within the broken lines in the figure drawings represent unclaimed environment only and forms no part of the claimed design.

The present invention relates to various serviette dispensers, commonly stored in bathrooms for hygienic purposes. An important component in the use of washcloths and napkins is their hygienically safe disposal.
